UNITED STATES PATENT OFFICE.

MATHEW CORCORAN AND CHARLES M. GATES, OF ROCK FALLS, ILLINOIS.

MACHINE FOR MAKING TUBS.

SPECIFICATION forming part of Letters Patent No. 317,516, dated May 12, 1885.

Application filed March 6, 1885. (No model.)

To all whom it may concern:

Be it known that we, MATHEW CORCORAN and CHARLES M. GATES, citizens of the United States, residing at Rock Falls, in the county 5 of Whiteside and State of Illinois, have invented certain new and useful Improvements in Machines for Making Tubs; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 Our invention pertains to machines for making tubs, particularly butter-tubs, and has special reference to certain novel mechanism for straightening and finishing the ends of such tubs.

20 In the drawings, Figure 1 is a side elevation, partly in section, of a machine embodying our invention. Fig. 2 is a cross-section in the line $\alpha\alpha$ of Fig. 1, and exhibits the mechanism for finishing the mouth or top of the tub. Fig. 3 shows the inner face of the 25 movable lever, to which are attached the knives for finishing the lower end of the tub, preparatory to the insertion of the bottom. Fig. 4 shows such lever moved aside to permit the removal of the tub and the placing of its 30 successor. Fig. 5 is a plan of the movable seat G^4 of the carriage G' .

The machine is intended to receive the tub after the latter is set up in truss-hoops, and 35 level both ends of the tub, chamfer the inside and smooth the outside of the upper end, smooth and chamfer the inside of the bottom, and cut an annular groove on the inner surface of the sides, near the lower end of the staves, 40 to receive and hold the bottom of the tub in place. This is accomplished by the necessary number and location of knives, hereinafter described, which operate on the tub as the latter is rotated laterally.

45 A is the frame of the machine, upon which is suitably journaled the horizontal shaft B.

C is a pulley fixed on the shaft B, by which the latter is driven by means of the belt C'.

D is an idle-pulley seated loosely on the 50 shaft B, and designed to carry the belt C' when the shaft B is at rest.

E is a chuck of the size and shape required

to fit the inside of the tub, and which is screwed or otherwise suitably fastened on the outer end of the shaft B.

F is the tub in position for operation, and which at that time consists merely of its staves, held in place by the temporary or truss hoops a. The tapering form of the chuck E wedges into the tub when the latter is placed thereon 60 with its mouth or top inward, and the rotation of the shaft B imparts a rotary movement to both the chuck and tub.

G is a short lever pivoted at its lower end to an adjustable carriage, G' , sleeved longitudinally on the laterally-adjustable plate G^4 in grooves, and provided at its upper end with the handle G^2 . The oscillations of the lever G are in a line at right angles with the inner end of the tub F, and the cutting-knives, hereinafter named, are placed on that face of the lever G next to the adjacent end of the tub F. Such cutting-knives are three in number, are seated in the lever G, in any suitable mode (preferably by means of a set-screw, b) adjustably, with their cutting-edges toward such tub. Of such knives, the central one, H, is termed a "leveler," and pares the upper ends of the staves to a uniform length. The inside knife, I, is termed the "inside rowel," and its function is to pare or chamfer the inner edge of the upper ends of the staves to a uniform surface. The outside knife, K, is termed the "outside-rim rowel," and is intended to smooth and 70 reduce to a uniformity the outside of the upper 80 end of the tub F, so as to permit the passage of an outwardly-fitting lid. This threefold cutting process is conducted in rapid succession, the knives H I K being placed in the proper mutual relation therefor, and held and 90 guided by means of the lever G, through the medium of the handle G^2 . By means of slots t in the frame A, parallel with the shaft B, and longitudinal slots s in the seat G' , and suitable set-screws, u , projected from below, 95 the plate G' , and thereby the lever G, is adjusted so as to bring its knives in suitable relation to tubs of different sizes. The chuck E employed corresponds with the size of the tub being operated on.

100 M is a hand-lever pivoted near its lower end, and placed in such relation to the lower or outer end of the tub F, when the latter is in position for being acted upon, that the knives

of such lever M, hereinafter described, may respectively come in contact with the proper portions of such tub.

The knives set on the inner face of the lever M are three in number, as follows: N is a leveler, whose function it is to reduce the lower end of the staves forming the tub F to a uniform length, finish off the same and prepare for the tub-bottom. O is an inside howel, designed to chamfer the inside of the lower edge of the tub, and reduce the same to a smooth condition and true circle. P is a croze located at such point on the lever M, and in relation to the inner circumference of the tub, as to form the annular recess on the inside of the tub, to receive and support the bottom of the tub.

All of the knives N O P are set adjustably in the inner face of the lever M, and, like the knives in the lever G, act in rapid succession, being held to their work and guided and controlled by the operator grasping the upper end of the lever M.

The part R, to which the lower end of the lever M is pivoted, is sleeved on the transverse rod S to permit of lateral adjustment of such lever; and the supports S', which hold the rod S, are adjustably attached to the floor in slots which run perpendicularly to the rod S, whereby the lever M may be adjusted to suit tubs varying both in length and diameter.

T is a fixed rest to support the lever M when the latter is moved aside to permit a change of tubs. The levers G and M can be used at the same time or successively.

The advantage of our machine is in the rapid

progress of the work, its thoroughness and correctness.

What we claim as our invention, and desire to secure by Letters Patent of the United States, is—

1. The combination of the shaft B, provided with the chuck E, the lever G, provided with the handle G², and with the knives H I K, and the plate G', such plate being adjustably seated on the frame A, and the lever G adjustably pivoted at its lower end to the plate G', perpendicular to the line of such first adjustment, whereby the attached end of such lever may be shifted in two directions, so as to adapt said knives to tubs of variant diameters and lengths, substantially as shown, and for the purpose described.

2. The combination of the shaft B, provided with the chuck E, the lever M, provided with the knives N O P, the rod S, supports S', and the part R, the lever M being pivoted at its lower end to the part R, the latter sleeved upon the rod S, and the supports S' adjustably attached to the floor in slots placed perpendicular to the rod S, whereby the pivoted end of the lever M is rendered susceptible of adjustment in cross directions, so as to adapt its knives to tubs of varying diameters and lengths, substantially as shown, and for the purpose specified.

In testimony whereof we affix our signatures in presence of two witnesses.

MATHEW CORCORAN.

Witnesses: CHAS. M. GATES.

JOHN G. MANAHAN,
BELLE M. MANAHAN.
